PENCIL SHARPENER

Emma M. Havranek, Omaha, Nebr.

Application December 3, 1932. Serial No. 645,607

9 Claims. (Cl. 120—94)

The present invention relates to sharpening device adapted for operation upon lead pencils and the like.

An object of the present invention is to provide a simplified and compact structure for sharpening lead pencils and the like to provide a conical point by the automatic rotation of the pencil in the operation of the machine, and wherein the machine or device may be adjusted so as to hold the pencil against rotation to produce a spade like or flat point on the end thereof.

The invention aims at the provision of a pencil sharpening device or machine which may be operated on the plunger principle by merely depressing a handle or the like so as to effect the operation of the cutter, and when adjusted, the rotation of the pencil.

The invention also provides an improved means for maintaining the cutter sharp, the sharpening device being automatic and operable by the reciprocating movement of the plunger.

A further object of the present invention is to provide an improved anvil or support for the pencil point adapted to hold the same in a predetermined position and which is automatically opened to receive the edge of the cutting element so that the latter may pass down beyond the point of the pencil and thus produce a clear, sharp point or edge to the extremity of the pencil point.

With the foregoing and other objects in view, the invention will be more fully described herein-after, and will be more particularly pointed out in the claims appended hereto.

In the drawings, wherein like symbols refer to like or corresponding parts throughout the several views.

Figure 1 is a front elevation of the device with a portion of the casing and the pencil holding device removed, the plunger being in raised position.

Figure 2 is a transverse section taken vertically through one side of the device on the line 2—2 of Figure 1, the dotted lines showing the relative position of a pencil.

Figure 3 is a rear side elevation of the device as shown in Figure 1.

Figure 4 is a horizontal section taken through the device on the line 4—4 of Figure 1.

Figure 5 is a front elevation of the device similar to Figure 1 but showing the pencil supporting means in place.

Figure 6 is a side elevation partly in section of the device showing the pencil support and showing the cutter in lowered position, the section be-

ing taken substantially on the line 6—6 of Figure 9.

Figure 7 is a rear elevation of the device showing the cutter and its parts depressed and showing the pencil holder in its relative position.

Figure 8 is a detail top plan view of the front cover section detached from the casing, and

Figure 9 is a top plan view of the device, with the cover plate of Figure 8 removed therefrom, showing the pencil holder and adjacent parts.

Referring now to the drawings, 10 designates the bottom or base of the pencil sharpener which is preferably of rectangular shape, although any suitable configuration and structure may be given the same. Mounted on the base 10 is a casing or frame 11 comprising side portions and joined by a top wall or plate 12, and the latter is provided centrally with an upstanding tube or sleeve 13 serving as a support for the plunger which operates the device. Within the tube 13 is disposed a plunger rod 14 upon the upper end of which is mounted a hollow handle 15, the latter telescoping at its lower end with tube 13 and adapted to move down over the tube when the handle 15 is depressed, as shown in Figure 6. The handle 15 with the plunger 14 is normally maintained in raised or extended position by means of an expanding spring 16 seated at its outer end within the handle 15 and at its other end within the bottom of the tube 13 on the cover 12, as shown in Figure 6, and the tube 13 is of sufficient length to accommodate the entire length of the spring 16 when the latter is compressed, as shown in Figure 6.

The plunger rod 14 extends down through the top 12 and is secured to a cross head 17. The cross head 17 extends transversely across the interior of the casing 11 and is curved or raised in its outer ends to engage guide rails 18 provided upon the inner opposite faces of the casing walls.

A shaft or pin 19 extends transversely through the central portion of the cross head 17 but is provided upon its forward end with a concavo-convex disc 20 which comprises the cutting or sharpening element. The opposite or rear end of the shaft 19 carries a ratchet wheel 21 adapted to bear at one side against a depending inwardly bowed flat spring 22 having a pawl projection 23 near its lower end adapted to engage an adjacent tooth of the ratchet wheel 21 when the cross head 17 is depressed so as to turn the wheel 21 with the shaft 19 and the cutting disc 20 a suitable distance depending upon the continued downward movement of the cross head. The ratchet wheel 21 and the spring member or pawl 22 thus com-

prise a means for intermittently turning or advancing the cutting disc 20 so as to present a new cutting edge upon each downward thrust of the cutter.

5 Means is provided for automatically sharpening the cutting edge of the disc 20. This means comprises a sharpening stone holder 24 having an elongated slotted shank 25 which is slidably disposed in inclined position, as shown in Figure 2
10 across the forward side of the cross head 17, and at one side of the shaft 19. A set screw 26 is secured through the slot of the shank 25 and threaded into the cross head 17, and a flat spring 27 is mounted on the outer headed end of the
15 set screw 26 and bears yieldingly against the shank 25 to frictionally hold the same in raised and lowered positions within the limit of the slot of the shank 25.

The lower end of the shank 25 is provided with
20 a shoulder or projection 28 which lies in the path of a pair of partially disposed shifting pins 29 and 30 so that as the cross head 17 approaches the end of its upper stroke, the shank 25 is arrested by means of engagement of the projection
25 of the pin 28 with the upper pin 29 so that further movement of the cross head draws the stone holder 24 downwardly at the rear side of the cutting disc 20. A suitable sharpening stone 31 is mounted in the holder 24 and is disposed to wipe
30 across the outer convex edge of the cutter disc 20 at each downward and upward stroke thereof. As the cross head 17 approaches the end of its lower stroke, the projection 28 strikes the pin or stud 30 and shifts the shank 25 upwardly so as to
35 wipe the stone 31 upwardly across the contact portion of the disc 20. In this manner, the sharpening stone 31 is moved in wiping engagement up and down against the adjacent edge portion of the disc 20, and as the disc is intermittently turned, the various portions of the disc are consecutively brought into position for engagement with the stone 31. The cutter 20 is thus automatically maintained in sharpened condition.

45 The upward stroke of the cross head 17, under action of the spring 16, is cushioned against shock by means of a felt or other suitably provided pad 32 which may be carried about the lower end of the plunger rod 14 at the top of the cross head 17.
50 The lower end of the rod 14 projects beyond the cross head 17 and is preferably provided with a resilient foot piece 33 of rubber or the like for arresting the lower movement of the plunger when depressed and to absorb shock at the end of the lower stroke of the cross head.

55 The resilient foot piece 33 is disposed in line with the pivoted section 34 of an anvil normally held in horizontal position by a spring 35 disposed between the anvil section 34 and the base plate 10, as shown in Figure 2. The pivoted section 34 is mounted on a transverse pivot pin 36 carried by the base 10 and extends rearwardly over the base from the forward fixed section 37 of the anvil upon which the point of the pencil, or other device being sharpened, is adapted to rest. The upper faces of the anvil sections 34 and 37 are relatively flat to accommodate the pencil point, and the adjacent end portions of the anvil sections are disposed in abutting relation to limit
70 the upward swinging of the hinged section 34 and to maintain the pencil point above the upper face of the anvil. The meeting ends of the anvil sections are disposed in the plane of the cutter 20 so that as the cutter 20 is advanced toward the
75 anvil the sharpened cutting edge of the cutter

enters the slot or space between the anvil sections which is opened by the foot 33 of the plunger, as shown in Figure 6.

Thus, the cutting edge of the cutter may pass downwardly beyond the extremity of the pencil point and thus produce a clear cutting action on the extremity of the pencil point. Preferably, the hinge section 34 of the anvil is provided with a flat guide projection 38 for directing the point of the pencil forwardly and downwardly upon the stationary or fixed section 37 of the anvil. This prevents breakage of the point when the cutter 20 is moved down into the slot which is opened in the anvil.

80 The pencil holder comprises a pivoted body member having an intermediate cylinder or sleeve portion 39 with opposed wings which extend to the sides of the casing 11 and are secured thereto by co-axial pivots 40. The pivots 40 are disposed near the lower end of the pencil holder so that the upper end thereof may freely swing back and forth on the pivots 40. The pencil holder is mounted on the upper portion of the casing 11 substantially opposite to the shaft 19 when the cross head 17 is in normal raised position. Rotatably mounted in the cylinder 39 is a socket 41 adapted to receive a pencil therethrough and which is provided with a pair of spring jaws 42 which extend upwardly beyond the socket and are arranged to grasp the opposite sides of a pencil 90 when the latter is inserted downwardly through the socket.

95 The socket 41 is provided on its upper end with an outstanding flange suitably toothed to provide a ratchet wheel 43 with which engages a spring 100 pawl 44 slidably seated across the inner side of the sleeve 39 and which is pivotally connected at its outer end to a double cam rocking lever 45 mounted intermediate its ends on a pivot 46 which is carried upon the adjacent wing of the pencil 105 holder. The opposite ends of the lever 45 are offset toward the adjacent side of the casing 11 and are so disposed as to be alternately engaged by the opposite ends of a double cam block 47 which is carried upon the adjacent side of the cross 110 head 17. The downward movement of the cam 47 engages the lower end of the lever 45 and moves the upper end thereof outwardly to lock the spring pawl 44 over with the teeth of the pencil socket ratchet 43 to turn the same while the upward 115 movement of the cam 47 engages the upper end of the rocking lever 45 and moves the spring pawl 44 to a new advanced position on the ratchet wheel 43. The relative lengths of the rocking lever 45 and the cam block 47, and the offset re- 120 lation between opposite ends of the rocking lever 45 is such that when the pencil holder is tilted forwardly away from the cross head 17 to a slight extent the upper end of the rocking lever 45 is disposed out of line with the cam block 47 and the lever 45 is thus rendered inactive as the cross 125 head and plunger are reciprocated.

130 The casing is provided with a front cover 48 preferably comprising a metal plate of suitable angular configuration to fit partly over the top of the casing and to close the front side thereof. The cover plate 48, as shown in Figure 3 particularly, is provided with an opening 49 upwardly through which the spring jaws 42 project for receiving a pencil. The opening 49 is of such size as to admit a 135 of a slight rocking movement of the pencil holder toward and from the cross head, and a shifting lever 50 is pivotally mounted in flat engagement against one wing of the pencil holder and projects upwardly through an inclined slot 51 provided in 140

the top portion of the cover plate 48. The slot 51 is inclined forwardly and inwardly so that as the shifting lever 50 is swung in the slot 51 the pencil carrier is swung outwardly at its upper end 5 so as to escape the cam block 47. The shifting lever 50 is frictionally held by its pivot against the wing of the pencil holder so that the shifting lever will stay in adjusted position. When the shifting lever 50 is swung inwardly the pencil holder is 10 swung forwardly and held in such position so that the pencil will not rotate during the operation of the cutter. The pencil may manually turn a complete half turn and the operation completed so as to effect a uniform cut or tapering of the 15 pencil from opposite sides.

In the normal operation of the device, the shifting lever 50 is swung outwardly toward the side of the casing 11 so as to hold the rocking lever 45 in the path of the double cam 47. A pencil is inserted 20 between the spring jaws 42 and down through the socket 41 until the lower end of the pencil rests upon the closed anvil, as shown in Figure 2. The operator now depresses the handle 15 and the plunger rod 14 forces the cross head 25 17 downwardly on the guide rails 18. During this downward movement the lower end of the cam block 47 strikes the lower end of the rocker 45 and turns the pencil through a predetermined distance depending upon the throw of the spring 30 pawl 44 and the spacing of the teeth of the ratchet 43. Further downward movement of the cross head 17 effects the upward shifting of the sharpening stone 31, as above described, and still further movement of the cross head 17 in a downward direction brings the ratchet wheel 21 into engagement with the spring ratchet 22 for advancing the cutting disc 20 through a desired distance.

As the cross head 17 reaches the lower end of its stroke the cutting edge of the cutter 20 engages 40 the lower end of the pencil and cuts or slices the same at the desired angle, depending upon the pivot mounting of the pencil holder.

Finally, the presser foot 33 of the plunger engages the movable portion of the anvil and opens 45 the same so that the cutter edge of the cutter 20 may pass down beyond the end of the pencil and into the slot of the anvil. When the handle 15 is released, the spring 16 raises the handle 50 with the plunger rod 14 and the cross head 17. During this movement, the sharpening stone 31 is wiped 55 across the edge of the cutting disc 20 to sharpen it, and the upper end of the cam block 47 engages the upper end of the rocker 45 so as to advance the spring pawl 44 into a new position 60 for engagement with the ratchet wheel 43. The parts are now in position for a second downward thrust of the cross head and plunger, and it is apparent that before the cutter 20 moves downwardly to any appreciable extent, the socket 41 which carries the pencil is turned to a slight degree 65 to present the pencil in a new position to the cutter 20. The repeated operation of the plunger thus uniformly cuts or sharpens the point of the pencil entirely thereabout. The structure 70 of the anvil is such that it holds the point of the pencil in line with the cutting disc 20 and releases the lower end of the pencil only when the cutting disc 20 is disposed close to the top of the pencil so that the cutting disc 20 holds the pencil from 75 sliding into the slot or opening in the anvil. The anvil is closed automatically by the spring 35 when the plunger rises so that there is no chance for the lower end of the pencil to slide into the slot of the anvil and become broken or damaged by 80 such movement.

It is obvious that various changes and modifications may be made in the details of construction and design of the above specifically described embodiment of this invention without departing from the spirit thereof, such changes and modifications being restricted only by the scope of the following claims:

What is claimed is:

1. A pencil sharpener comprising a pencil holder, a reciprocating member, a disc cutter carried by said member, means for guiding said reciprocating member in a plane oblique to the axis of the pencil holder and intersecting the lower end thereof, turning means for the cutting disc, and stationary means cooperating with the turning means for actuating the latter to turn the disc upon each stroke of the reciprocating member for presenting a different edge portion of the cutting disc to the pencil at each stroke of the member. 80

2. A pencil sharpener comprising a pencil holder, a reciprocating member, guide means for said member to hold the same for movement in a plane oblique to the lower end of the pencil, a rotary cutter mounted on the reciprocating member, means for turning the cutter, stationary operating means for the turning means to advance the cutter upon each stroke of the reciprocating member, and a sharpening device mounted on the reciprocating member in contact with the cutter to sharpen the cutting edge thereof upon rotation 95 of the cutter. 100

3. A pencil sharpener comprising a pencil holder, a reciprocating member, a disc mounted on the member in position to engage the pencil upon movement of said member, means for turning the cutting disc by movement of the member, a sharpener for the disc mounted on the reciprocating member, means carried by the sharpener for moving the same against the cutting edge of the disc, and stationary means for actuating the sharpener upon the movement of said member. 110

4. A pencil sharpener comprising a pencil holder, a reciprocating member, a cutting disc on said member to engage the pencil at each stroke of the member, turning means for the cutting disc 120 operable by movement of the member, a sharpener carried by the member engaging the disc, movable means for the sharpener operable upon movement of the member.

5. A pencil sharpener comprising a pencil holder, a plunger, a cross head on the plunger, a disc rotatably mounted on the cross head for engagement with the pencil, a sharpener on the cross head engaging the disc, turning means on the cross head connected with the disc, stationary 125 means for operating the disc turning means when the cross head is depressed by the plunger, and stationary means operable upon the sharpener moving means upon movement of the cross head to move the sharpener back and forth across the 130 edge of the cutting disc. 135

6. A pencil sharpener comprising a pencil holder, a reciprocating member, a cutting disc mounted on said member, turning means for the disc on said member, a stationary pawl for engagement 140 with the turning means to advance the disc upon each stroke of the reciprocating member, a sharpening device on the reciprocating member engaging the edge of the disc to sharpen the same by rotation of the disc, a projection carried by the 145 sharpener, and spaced stops fixed adjacent the projection for engagement thereby to wipe the sharpener across the edge of the disc at each stroke of the reciprocating member.

7. A pencil sharpener comprising a pencil hold- 150

er, a reciprocating member, a cutting disc on said member adapted to engage the inner end of the pencil, an anvil supporting means for the pencil and having a pivoted part yieldingly held in raised position to hold the point of the pencil in line with the cutting disc, and a projection on the reciprocating member adapted to engage said pivoted part of the anvil for depressing the same upon the inward movement of the reciprocating member to provide a slot for the reception of the lower portion of said disc when moved below the point of the pencil.

8. A pencil sharpener comprising a reciprocating member, a cutting disc carried by the member, turning means operable by the member for turning the disc, a pencil holder disposed adjacent the reciprocating member and adapted to receive a pencil for engagement with said disc, turning means on said holder for rotating the pencil, and cooperating means upon the holder and said reciprocating member for actuating the rotating means upon the movement of the reciprocating member.

9. A pencil sharpener comprising a reciprocating member, a cutting disc carried by the member, turning means operable by the member for turning the disc, a pencil holder disposed adjacent the reciprocating member and adapted to receive a pencil for engagement with said disc, turning means on said holder for rotating the pencil, and cooperating means upon the holder and said reciprocating member for actuating the rotating means upon the movement of the reciprocating member.

10. A pencil sharpener comprising a reciprocating member, a cutting disc mounted on said member, a ratchet wheel connected to said disc to turn the same, a stationary pawl arranged in the path of said ratchet wheel for turning the same and the disc upon the movement of the reciprocating member, a sharpener carried by the reciprocating member for engaging the disc, stationary means cooperating with the sharpener for reciprocating the same on said member to move the sharpener across the edge of the cutting disc, a pivoted pencil holder mounted adjacent the reciprocating member for holding a pencil in line with the cutting disc, a cam on the reciprocating member, a rocker on the pencil holder having spaced ends lying in the path of said cam for reciprocating the rocker upon the movement of the member, turning means carried by the pencil holder connected to said rocker for rotating the pencil upon movement of the rocker, and means connected to the pencil holder for swinging the latter to move the rocker out of line with said cam for maintaining the pencil against turning during the reciprocation of said member.
